UNITED STATES PATENT OFFICE.

SOLOMON WISOTZKY, OF NEW YORK, N. Y.

TROUSERS.

1,070,867.

Specification of Letters Patent.

Patented Aug. 19, 1913.

Application filed January 23, 1912. Serial No. 672,883.

To all whom it may concern:

Be it known that I, SOLOMON WISOTZKY, a citizen of the United States, residing in the borough of Manhattan, city, county, and 5 State of New York, have invented certain new and useful Improvements in Trousers, of which the following is a specification.

The object of this invention is to improve the appearance of the inner side of a pair 10 of trousers at the waist-band edge thereof, while at the same time providing an extremely simple, durable and strong waist-band structure through which the button attaching means will pass.

Another object of the invention is to provide a stout reinforcing band and to secure 15 it to the upper waist-band edge of the trousers and to cover said reinforcing band by means of a freely hanging curtain so that 20 said curtain will conceal the line of stitches securing the lower edge of the reinforcing band to the trousers. This line of stitches passes through the trousers and is necessarily of black or other dark colored thread. 25 The curtain is usually made of some light colored material and it is desirable that the line of black stitches securing the reinforcing band to the trousers should be concealed by the curtain. In the ordinary 30 practice this line of black stitching passes through the curtain and is unsightly. By my construction this line of stitches is concealed by the curtain so that the waist-band portion of the trousers has a neat and pleasing 35 appearance.

In the drawings, Figure 1 is a view of a pair of trousers provided with my invention; Fig. 2 a detail vertical sectional view of the upper or waist-band edge of the 40 trousers showing the reinforcing band and curtain structure applied thereto; and Fig. 3 a detail sectional perspective view of the curtain and reinforcing band.

Referring to the various parts by numerals, 1 designates the trousers; 2 a broad curtain secured to the inner side thereof along the waist-band edge, and 3 a narrow reinforcing band connected to the curtain and to the trousers along the upper edge thereof 45 and connected to the trousers along the lower edge of said band, as will be more fully hereinafter described. The reinforcing band is first secured to the curtain by an undulating line of stitches 4. These stitches

are preferably made of white thread as the 55 curtain is usually made of some light material and it is desirable that this line of stitches be as inconspicuous as possible. By this undulating line of stitches the reinforcing band is connected to the curtain 60 in such manner as to hold the curtain flat and prevent it buckling or wrinkling. The upper edges of the curtain and the reinforcing band are brought together, folded inwardly and stitched to the trousers along 65 the upper edge thereof, as shown clearly at 5 in Fig. 2. The two bands are folded as shown in said figure so that the line of stitches connecting them to the trousers will be concealed by the main parts of the bands 70 and so that the curtain will be on the inner side of the trousers and will conceal the reinforcing band. The curtain is broader than the reinforcing band and extends a considerable distance below the lower edge 75 of said band. The lower edge of the reinforcing band is stitched directly to the trousers, the lower edge of said band being first turned up to form the double portion 80 and the stitches passing through said double portion and through the trousers. This line of stitches does not pass through the curtain, the curtain being free of the waist-band below the undulating line of stitches 4. This permits the curtain to be folded or 85 turned upwardly to expose the lower edge of the reinforcing band, so that the operator may readily stitch said band along its lower edge to the trousers. This line of stitches passes through the trousers and is 90 usually of dark thread. It is desirable that this line of stitches should not show through the curtain for the reason that the curtain is usually made of light material and a line of stitches therethrough of dark thread 95 would be very unsightly.

The reinforcing band is preferably made of buckram or like strong fabric. This buckram band gives the requisite stiffness to the upper edge of the trousers and forms 100 a strong structure through which the button securing means may pass. The buttons 7 are securely attached to the inner side of the trousers near the upper edge of the curtain by stitching or other fastening means 105 which are preferably passed through the buckram reinforcing band and through the trousers.

My invention is particularly adapted for use in knee trousers, but, of course, it may be applied to trousers of any length.

What I claim is:

- 5 The combination with a pair of trousers, a broad non-elastic curtain, a narrow non-elastic reinforcing band arranged on the inner side along the upper or waist-band edge of the curtain, the upper edges of the curtain and the band being turned inwardly and downwardly, the reinforcing band being between the curtain and the trousers, a line of stitches passing through the turned down edges of the curtain and the band, 10 said stitches being concealed by the curtain, a line of stitches connecting the lower edge of the reinforcing band to the trousers said 15 line of stitches being concealed by the curtain,

tain, a line of stitches connecting the curtain to the reinforcing band and substantially midway between the upper and lower edges of the reinforcing band, whereby the said curtain will be free of the reinforcing band at the lower edge thereof and the curtain will extend a considerable distance below said band, and a series of buttons arranged on the curtain and secured in position by means passing through the curtain, the reinforcing band and the trousers.

In testimony whereof I hereunto affix my signature in the presence of two witnesses.

SOLOMON WISOTZKY.
